MACHINE FOR MAKING PAPER
RECEPTACLES

Carl A. Moeller, Randolph, Mass., assignor to
Norfolk Paper Co., Inc., Randolph, Mass., a corporation of Massachusetts

Application July 30, 1940, Serial No. 348,475

3 Claims. (Cl. 93—55.1)

The present invention relates to machines for making paper containers and more particularly to machines for securing the end closure in a paper cylinder of a cover or top for a paper can.

Caps or covers for paper cans are commonly made so that they fit snugly over the end of the can, as it is desirable to have them retained securely in position by the frictional engagement between the inner and outer surfaces of the cap and can walls. With such a close fitting cover, however, difficulty is experienced in starting the cover over the open end of the can.

Furthermore, it is common practice to form the cylindrical body portion of the cap or cover by cutting off sections of appropriate length from a long rotating tube or cylinder by means of a stationary tool or knife. The pressure of the knife in this severing operation causes a slight inward turning or a burring at the cut edge, which further interferes with the starting of the cover over the end of the can.

In order to overcome this difficulty it has been a common practice to expand or flare slightly the open end of the cover or cap so that it may be easily started over the end of the can. This expanding or flaring operation is performed as a separate, distinct, and additional operation after the cap or cover has been otherwise completed by the assembling and securing of the disk or closure in the open end of the cap or cover cylinder.

It is the object of the present invention to provide a machine which shall, in a single operation, secure the end closure in the cover by the usual rolling or crimping operation, and at the same time give to the opposite or open end the slight flare above described.

With this object in view, the present invention consists in so constructing and forming the support or mandrel for the cylinder of the cover that during the crimping or rolling operation, whereby the end closure is secured in one end of the cylinder, the opposite end will simultaneously be flared or expanded sufficiently to insure easy positioning of the cover on the end of the can, yet without liability of damage to the cover cylinder.

More specifically, the present invention contemplates the provision of a cylinder support or mandrel with an expanding portion over which the open end of the cover is forced when the closure disk is secured in the other end of the cylinder by the roller or crimping die, gripping means on the support or mandrel being arranged to yield sufficiently to permit the slight longitudi-

nal or axial movement of the cylinder required to flare or expand the open end of the cover yet at the same time holding the cover cylinder securely in position without rotation.

5 In the accompanying drawing which illustrates what is now considered the preferred form of the present invention, Fig. 1 is a side elevation of a well known type of machine adapted for securing closure disks in the end of a paper cylinder, and Fig. 2 is a top plan view of a portion of the same, showing the parts for holding and presenting the rotating forming die; Fig. 3 is a side view, partly in section, of one of the supporting arms with its mandrel or support and 10 the forming die and a completed cover in operative position; Fig. 4 is an enlarged detail of a portion of Fig. 3 showing parts of the mandrel, die and support, and Fig. 5 is a perspective view, 15 with a portion cut away, of the completed can cover with the closure secured in one end with the flare formed at the other or open end of the cover.

As shown in Figs. 1 and 2 of the drawing, the machine comprises essentially a rotary turret 25 having four horizontal arms, each carrying at its free end a cylinder mandrel provided with expanding grippers for holding the cylinder of the cover securely thereon and presenting it to a rotating forming die mounted upon a rotating motor driven spindle and continuously reciprocated toward and from the mandrels as they are successively presented. Both turret and spindle are automatically turned and reciprocated, respectively, through suitable connections in timed relation, and the gripping devices are similarly actuated to grip and release the cover cylinder at appropriate times. A suitable ejector is also provided for automatically pushing the completed cover off the mandrel after the forming and flaring operations. The mandrel is provided with an expanding or flaring section to expand the open end of the cover, the gripping devices being yielding so as to permit slight axial movement of the cover cylinder over the mandrel to 30 bring the end of the cover cylinder into engagement with the flaring portion of the mandrel during the final stage of the spinning operation.

As shown in Fig. 1, the rotary turret, indicated generally at 11, comprises four horizontal arms 35 13 mounted upon a vertical spindle 15, rotatably secured in the bearing block 17 of the frame 19 of the machine. The turret is given intermittent turning movements through successive 90° angles by means of a Geneva motion comprising 40 the disk 21 secured to the bottom of the shaft

15 and having four radial slots 23 formed in the lower surface thereof to receive a stud 25 on the arm 27 fixed upon the vertical shaft 29 driven by the bevel gears 31 on the horizontal shaft 33. This shaft is turned through reducing gears 35 and 37 driven by the motor 39 through belts 41 and 43 and speed reducing pulleys.

Fixed upon the outer end of each of the turret arms 13 is a mandrel having a cylindrical body portion 45 to receive upon it the cylindrical body 47 of the cap or cover, and also having a flange of larger diameter connected with or joined to the cylindrical portion 47 by the curved surface or fillet 51.

The gripping devices for holding the cylindrical portion of the cover upon the mandrel comprise arcuate metallic shoes or grippers 53 mounted in an annular recess in the cylindrical face 45, which shoes are carried upon radial rods 55 slidably mounted in bores 57 in the mandrel. The inner ends of the rods are provided with conical heads 59 arranged to be engaged by the conical head 61 on the horizontal actuating rod 63 within a bore 64 in the turret arm. A bell-crank lever 65 pivoted upon the bracket 67 upon the turret arm is arranged to engage at one end the actuating rod 63. The other end of the bell-crank lever carries a threaded bolt 68 the head of which engages and is raised by the fixed inclined cam 69 as the turret arm turns to a position in line with the forming die, thereby causing the gripping shoes to move outwardly in their recess.

Upon the outer face of each shoe in position to engage the inner surface of the cylinder body of the cap or cover is a facing of rubber 71, conveniently in the form of a rubber band overlying the four gripping shoes and of a substantial thickness. The bolt 68 on the bell-crank lever 67 is so adjusted with respect to its actuating cam 69 that the rubber faced gripper shoes 53 will engage the cap body under sufficient pressure to hold the cap from turning on the mandrel when the latter is in operative position opposite the forming die yet permit a limited axial movement of the cover toward the flange 49 of the mandrel and into operative engagement with the fillet 51 under the pressure of the forming die, thereby to flare or expand slightly the open end of the cover, as shown at 73 in Figs. 3, 4 and 5. If too light a pressure or grip is exerted by the shoes, the cap will be forced inwardly so far that its inner edge will be split, and if too heavy a pressure or grip is employed, the cap will be so securely held that no axial movement is permitted and consequently no flare is given to the edge of the cover. The cap body may even be ruptured by excessive pressure of the grippers.

The forming die, indicated generally at 75, is mounted on the rear end of a rotating shaft or spindle 77 driven by the belt 79 from the motor 39. The shaft is mounted in the bearings 81 on the head or block 83 which is slidably mounted upon the frame 19, and is reciprocated by means of the cam roll 85 on the bottom of the carriage, engaging the cam slot 87 on the cam 89 on the shaft 33.

The face of the forming die is shaped to turn and crimp over the outer margin of the end disk 91 and the end 93 of the body portion into locking engagement, as shown in Fig. 4, when the die is moved toward the mandrel. While the face of the crimping die may be of any desired construction, a satisfactory and well-known

form is that illustrated in Figs. 3 and 4, where the crimping members consist of studs 95 provided with grooved or notched crimping recesses 97 and secured in position by the locking screws 99.

Means are provided for removing the formed cover or cap from the mandrel by means of an ejector actuated by the rotary motion of the turret. The ejector is shown as a circular plate 101, normally positioned within a recess in the front end of the mandrel, being mounted on the studs or rods 103 secured at their rear ends to the sliding collar 105 splined upon the turret arm and having depending therefrom the stud 107 carrying at its lower end the contact member 109 adapted to engage the fixed cam 111, (see Fig. 2), thereby to force the collar along the arm and the ejector plate outwardly from the mandrel to release or remove the box cover therefrom, the plate then being in the position shown in the lowermost mandrel, Fig. 2. The plate is returned to inoperative position by springs 113 connecting the collar 105 with the bracket 67 fixed upon the turret arm.

The completed cover or cap, after it has been ejected from the machine, is of the shape shown in Fig. 5, with one end closed by the disk 91 with its peripheral edge and the end of the cylindrical cap body rolled or crimped together, while the opposite open end of the cap is slightly flared or expanded, as indicated at 73.

In operation, the motor 39 runs continuously, rotating the crimping die 75 and reciprocating it intermittently towards and from the mandrels as they are presented one after another in succession. Assuming the turret rotates in the direction shown by the arrow in Fig. 2, the operator, standing at the station corresponding to the position of the mandrel at the top of the figure, places upon the mandrel a cover or cap body into the end of which has been manually pressed an end disk. At this point the grippers are withdrawn so that the cover body may be slipped easily over the mandrel until its open end is close to the fillet. When the turret completes its next rotational step, the cam 69 actuates the grippers causing them to expand and grip the body. The mandrel and assembled cover are now opposite the forming die, which is advanced by the cam 89, and through its rotational action crimps or folds the parts together. During the crimping operation, as pressure is brought upon the parts, the rubber face 71 of the gripping shoes yields or is distorted slightly to permit the open end of the cover body to be forced over the fillet 51 or the curved portion of the mandrel, thereby permanently expanding or flaring the edge or end of the cover.

The die is now withdrawn and the turret is rotated another 90°, whereupon the formed cover will be ejected, another assembled cover brought into position opposite the forming die, and the crimping and expanding operations repeated.

While in the specification and accompanying drawing there has been described and shown what is now considered to be the preferred form of the present invention, it is to be understood that such invention is not limited thereto but may be embodied in other forms and arrangements of parts within the language of the appended claims.

Having thus described the invention, what is claimed is:

1. In a machine for making paper receptacles, the combination with a rotary forming die, of

means for advancing the die axially to secure the end closure in a paper cylinder, a support for the cylinder, said support comprising a portion adapted to be received within the paper cylinder, an outwardly flaring portion for engaging and expanding the open end of the paper cylinder, bodily yielding gripping means for engaging the inner surface of the inner wall of the cylinder, and devices for actuating the gripping means to prevent relative movement between the contacting surfaces of the cylinder and the gripping means while permitting said means to yield bodily to permit a limited movement of the end of the cylinder over the flaring portion of the support under the pressure of the die to expand 15 permanently the open end of the paper cylinder.

2. In a machine for making paper receptacles, the combination with a rotary forming die, of means for advancing the die axially to secure the end closure in a paper cylinder, a support for the cylinder, said support comprising a cylindrical portion adapted to be received within the paper cylinder, an outwardly flaring portion for engaging and expanding the open end of the paper cylinder, gripping means having rubber 20 facings for engaging the inner surface of the wall of the cylinder, and devices for actuating the gripping means to cause the rubber facings to grip the cylinder and to prevent relative movement between the contacting faces of the cylin- 25

der and facings while allowing the rubber facings to yield to permit a limited movement of the end of the cylinder over the flaring portion of the support under the pressure of the die to expand permanently the open end of the paper cylinder.

3. In a machine for making paper receptacles, the combination with a rotary forming die, of means for advancing the die axially to secure the end closure in a paper cylinder, a support for the cylinder, said support comprising a cylindrical portion adapted to be received within the paper cylinder, an outwardly flaring portion for engaging and expanding the open end of the paper cylinder, gripping means comprising rigid, articulate clamping shoes provided with rubber engaging faces for engaging the inner surface of the wall of the cylinder, and devices for actuating the gripping means to cause the rubber faces to grip the cylinder and to prevent relative movement between the contacting surfaces of the cylinder and the rubber facings while permitting said faces to yield with respect to the rigid shoes to permit a limited movement of the end of the cylinder over the flaring portion of the support under the pressure of the die to expand permanently the open end of the paper cylinder.
